DOOR PULL

Sherwin L. Watford, 590 E. Buchtel Ave.,
Akron, Ohio 44304

Filed Oct. 16, 1972, Ser. No. 300,126

Term of patent 14 years

Int. Cl. D8—06; D4—04
U.S. Cl. D8—159

FIG. 1

FIG. 2

FIG. 3

FIG. 1 is a perspective view showing my new design for a door pull.

FIG. 2 is a rear elevational view thereof.

FIG. 3 is a side elevational view thereof.

The opposed side is identical with that shown in FIG. 3.
I claim:

The ornamental design for a door pull, as shown and described.
